UNITED STATES PATENT OFFICE

CHARLES T. CHANDLER, OF EUSTIS, FLORIDA, ASSIGNOR TO CARMAN & CO., INC., OF NEW YORK, N. Y., A CORPORATION OF NEW YORK

GARMENT PROTECTOR

Application filed July 22, 1931. Serial No. 552,507.

This invention relates to paper articles such as are used largely by garment cleaners to cover or enclose one or more garments hung on a shoulder supporter, the latter usually 5 having means whereby it and clothing supported thereby can be delivered to a customer in protected condition and hung on a closet hook or elsewhere.

One of the most common types of such 10 garment protectors consists of a flat tubular enclosure, open at the bottom and having a tapered top formed by triangular folding of the upper corner portions, an opening for the hook of the usual shoulder hanger being 15 provided at the apex of the tapered top. Such garment protectors, especially when made of two distinctly different kinds of paper one of which is liable to be comparatively weak in substance, such as transparent paper like 20 cellophane or glassine, are sometimes found to be undesirably weak at the apex around the opening referred to, and liable to be torn by the presence therein of the usual hook member of a shoulder hanger.

25 The object of the present invention is to overcome the weakness of the protector at its apex, or in other words to strengthen the protector around that portion in which a hanger is to be located, so as to better withstand the shocks and wear to which the device 30 is liable to be subjected when in use.

With the above object in view, the invention consists in the structure of the articles, substantially as hereinafter described and 35 claimed.

Since the articles are illustrated as made from two webs or strips of paper, the terms "front" and "rear" will be employed in referring to the accompanying drawing, to distinguish the two webs or sections from each other. It is to be understood however that such terms are only employed for the sake of convenience and not of limitation, as the articles 45 may bear printed matter on either surface, and of course when so printed the surface bearing the printed matter would be considered the front of the article.

Of the accompanying drawing:—
50 Figure 1 is a rear elevation of one of the

articles as it would appear at a preliminary point of its manufacture.

Figures 2 and 3 are, respectively, rear and front elevations of a completed article.

Figure 4 is a section view taken along line 55 4—4 of Figure 3.

Similar reference characters indicate similar parts or features in all of the views.

In the manufacture of the articles, two webs of paper 12 and 13 are joined by marginal seams 14, and transversely cut at such longitudinal points or distances as necessary to produce articles of such length as may be desired. They may, of course, be much longer than illustrated. Then, as heretofore produced, corner portions 15 are diagonally folded and adhesively secured, the folding being so gaged as to leave an opening at the apex 16 for the passage of the hook portion of a hanger. As so far described, the steps 70 of manufacture are well known.

In the present structure the front member 13 is preferably of thin translucent paper, and it is usually of much less strength than the rear member 12, and therefore the said member 13 is the one which especially needs strengthening adjacent to the apex opening 16.

In carrying out the present invention, I 80 preferably employ strong reinforcing material such as kraft paper or gummed cloth, and cut the same into strips having substantially the form illustrated at the top of Figure 1, so that each reinforcing piece has parallel ends while the edges from end to end are correspondingly salient and re-entrant. This enables the reinforcing pieces or strips to be produced with absolutely no waste of material.

Either manually or by automatic machinery, a reinforcing strip is adhesively connected to the front member 13 at the mid-length of its straight edge, before any folding is done, and in such position that while its body or main portion 17 is adhesively 95 secured to said member 13 over a substantial area thereof, there will be two wing portions 18 projecting above said straight edge. The next step, also effected either manually or by automatic machinery, is that the desired an- 100

gular portions of both the front and rear members of the article are folded to the position illustrated in Figure 2, the wing portions 18 being folded over simultaneously therewith, suitable adhesive material being employed to ensure retention of the shoulder portions 15 and the wing portions 18 in the positions illustrated by comparing Figures 2, 3 and 4.

10 Having now described my invention, I claim:-

15 A garment protector comprising two marginally connected sections of paper one of which is thinner than the other, and a complete reinforcement for the thinner member, the upper corners of said sections of paper and portions of the reinforcement being triangularly folded, the central portion of the reinforcement extending across and secured 20 to the thinner member with laterally spreading wing portions thereof folded over and secured to the other section of paper, the complete article having an opening between said folded portions, said opening being of a size 25 to permit the passage of the hook of a garment hanger.

In testimony whereof I have affixed my signature.

CHARLES T. CHANDLER.
